(57) CLAIM

The ornamental design for the laptop stand, as shown and described.

DESCRIPTION

FIG. 1 is a front perspective view of a laptop stand showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view thereof, but showing the laptop stand in use with a laptop shown in broken lines. The laptop shown in broken lines is included for environmental purposes only and forms no part of the claimed design.
